SECONDARY ELECTRIC CLOCK

Filed Sept. 6, 1924

FIG. 1.

FIG. 2.

FIG. 3.

Inventor

Thaddeus S. Casner,
By Watson, Cott, Morse
and Grindler. Attorney

UNITED STATES PATENT OFFICE.

THADDEUS STEPHENS CASNER, OF PLAINFIELD, NEW JERSEY, ASSIGNOR TO RADIO ELECTRIC CLOCK CORPORATION, OF NEW YORK, N. Y., A CORPORATION OF DELAWARE.

SECONDARY ELECTRIC CLOCK.

Application filed September 6, 1924. Serial No. 736,372.

The present invention relates to clocks and more particularly to secondary electric clocks.

It is an object of this invention to provide a novel and improved form of electric secondary clock.

More particularly, it is an object of this invention to provide a secondary clock in which all gearing, except the usual reducing gearing, between the hand shafts is eliminated, thereby greatly reducing in number the requisite moving parts so that the clock is easy to construct and assemble, may be quickly repaired, and may be made small in size while at the same time affording positive and accurate operation.

A still further object of this invention is to provide in a secondary electric clock positive actuating means operative throughout a full circle and at a number of points equivalent to the number of impulses received by the clock in an hour.

In the accompanying drawings, there is disclosed by way of example one embodiment of the invention, it being understood that various modifications and arrangements of parts may be made therein without departing from the spirit of the invention, as set forth in the appended claims.

In said drawings:

Figure 1 is a front elevation of the clock, the casing and dial being omitted for the sake of clearness.

Figure 2 is a vertical section on line 2—2 of Figure 1.

Figure 3 is a front view of a portion of the mechanism on a much larger scale.

The frame of the clock comprises essentially the back plate 10, having the circumferential flange 11 struck up therefrom, the front plate 12 having the circumferential flange 13 adapted to fit snugly over the flange 11 and the bearing strip 14 extending diametrically across, parallel to, and spaced above, the front plate 12 and fastened thereto by the screws 15. The front and back plate flanges are secured together by any suitable means, such as the rivets 16.

Rotatably supported in the bearing strip 14 is the hour sleeve 17, and extending through this hour sleeve and having its rear end journaled in the bearing 18 pressed into an aperture in the center of the part

20 mounted in the plate 10 is the minute shaft 19, the minute shaft and hour sleeve being connected by the usual twelve to one reducing gearing R. The hour and minute hands H and M are supported respectively on the outer ends of the hour sleeve and minute shaft.

Spaced from and surrounding the inner end of the minute shaft 19 is the soft iron magnetic core 20, having the reduced rear end 20a pressed into an aperture in the rear plate 10 and carrying at its center the bushing 18, previously mentioned. The spool 21 is pressed tightly over the core 20 and carries a winding connected in circuit with a master clock, and adapted to be energized periodically, preferably at minute intervals.

Mounted on the shaft 19 and held in position between the pinion 22 and the collar 23 is the disk-shaped armature 24 lying in the same plane as the front plate 12, whose center is cut away as shown. This armature disk is formed of soft iron and is provided with sixty teeth of equal size and similar shape formed around its periphery. These teeth are formed as best shown in Figure 3, each by one radial line 25 and a chordal line 26.

Similar teeth of the same number and spacing are provided upon the inner periphery of the opening in the front plate 12, which thus constitutes a pole piece or annular core, and are defined by the lines 27 and 28, and if desired there may be grooves 29 relieving the teeth. The diameters of the opening in the front plate 12 and of the armature disk 24 are such that the tips of the teeth on the two parts have just sufficient clearance to allow the armature disk to rotate freely.

Considering Figure 3, the dotted position of the teeth on the armature disk represents the normal "at-rest" position thereof, and it will be noted that the edges 28 are not exactly parallel to the edges 26 but converge toward each other in a counter-clockwise direction. When the winding on the magnetic core 20 is energized, a magnetic circuit is formed through the back plate 10, front plate 12, shaft 19, core 20, armature disk 24, and the air gap between the corresponding pairs of teeth on the parts 12 and 24, all of these variously mentioned parts

being formed of suitable magnetic material. As is well known, the lines of force from a magnet always tend to assume the shortest possible length, and for this reason, the disk 24 will be rotated in the direction of the arrow of Figure 3 in order to shorten the gap between the teeth, the minimum length of this gap being attained when the disk reaches the full line position, as shown in this figure.

A disk or roller 30 of insulating material, such as hard rubber or fiber, is mounted upon a leaf spring 31 carried by the bracket 32, fastened upon the front plate 12 and fits 16 in an opening 33 therein. The spring normally presses the roller downwardly into the recesses between two adjacent teeth on the armature, as shown in the dotted lines in Figure 3, to hold the armature in its normal 20 "at-rest" position against rotation. When the electromagnet is energized, as it will be at minute intervals, where they are sixty teeth on armature 24, the armature will be moved from the dotted line position to the, 25 full line position, Figure 3, so that the tips of the teeth on the two parts are nearest to each other, since the armature moves into a position which enables the flux to pass across the smallest possible air space.

30 By this movement, the roller 30 is raised against the action of the spring 31 from its dotted line position to full line position, Figure 3, in which latter position it is resting on the point of one of the teeth of the armature 24. When the magnet is de-energized, the spring 31 acts to move the roller 30 downwardly and to continue the forward movement of the armature until the roller again contacts with two adjacent teeth and 35 can move downwardly no more, this action resulting from the fact that the tip of the tooth has already moved beyond a radial line connecting the shaft 19, with the pivot of the roller 30. The armature will now occupy 40 the position shown in dotted lines in Figure 3, having moved one-sixtieth of a revolution, and the electromagnet may be again energized at the termination of another minute to advance the armature another tooth and 45 thereby advance the hands.

It is apparent that the number of moving parts of the clock have been reduced to a minimum and all gearing eliminated, except the reducing gearing between the hand shafts which cannot be dispensed with where two hands are employed. The individual parts of the mechanism are of great simplicity, easy fabricated, and are very durable, no springs, with the exception of the single leaf spring 31, being employed, and weights are entirely eliminated. The absence of gearing and springs renders the usual spring clutch placed between the minute shaft and the clock gearing unnecessary, and in order 50 to set the clock it is only necessary to rotate

the minute hand to the desired position, the armature 24 rotating idly and the roller 30 riding freely over the teeth.

By applying the rotating force throughout the periphery of the armature, a more positive action is attained and lateral and canting thrusts eliminated so that the shaft bearings will wear longer.

Having thus described my invention, what is claimed as new and desired to be secured by Letters Patent is:

1. In a secondary electric clock, in combination, a wheel having peripheral projections constituting an armature, an annular member in the same plane as said disc and having corresponding inwardly disposed projections, an electromagnet in circuit between said annular member and disc, means to periodically excite said magnet to cause magnetic flux to flow across the gap between said sets of projections and move said armature a portion of the distance between two projections on either member and spring means to complete the movement over said distance.

2. In a secondary electric clock, in combination, a wheel having spaced peripheral projections constituting an armature, an annular member having similarly spaced, inwardly disposed, projections constituting a pole piece, an electromagnet, adapted to receive periodic impulses, interposed in circuit between said pole piece and armature remote from the gap between said projections, each energization of said magnet causing said projections to attract each other and rotate said armature a portion of the distance between adjacent projections, and means to complete the rotation over said distance and to position said armature for magnetic movement by the next impulse.

3. In a secondary electric clock, in combination, a back plate, an annular front plate connected thereto, an armature disc rotatively supported in the plane of said front plate, a shaft supporting said armature, an electromagnet surrounding said shaft and adapted to receive periodic impulses, opposed teeth on said disc and front plate having a gap between said teeth being of such configuration that the magnetic flux crossing said gap rotates said disc a portion of the peripheral pitch of a tooth at each impulse, and a detent for completing the rotation to full pitch distance and for positioning said teeth on the armature in operative relation to said other teeth for the next impulse.

4. In a secondary electric clock in combination, a wheel having a plurality of peripheral projections constituting an armature, an annular pole piece having a plurality of inwardly disposed projections, a shaft for said armature and an electromagnet surrounding said shaft to magnetize said armature and pole piece to cause partial rotation of said

armature, and means to cause additional rotation to position the projections one space forward.

5. A secondary electric clock including in combination, a flat back plate, an annular front plate parallel thereto, an armature disc rotatably mounted in the plane of said front plate, an axle for said disc journaled in said back plate, and an electromagnet having a core concentric with said axle.

6. A secondary electric clock including in combination, a back plate, an annular front plate parallel thereto but spaced therefrom, an armature disc rotatably mounted in the plane of said front plate, an axle for said disc journaled in said back plate, and an electromagnet between said back plate and disc, the core of said magnet surrounding said axle for the purpose set forth.

7. A secondary electric clock including in combination, a back plate, a peripheral flange thereon, an annular front plate, a peripheral flange thereon, said flanges interfitting, an armature disc in the opening in said annular flange, a diametrically disposed bearing plate

carried by said front plate, an axle for said disc journaled between said back plate and bearing plate, an electromagnet surrounding said axle and adapted to be energized periodically and means on said disc and front plate cooperating to rotate the disc upon energization of said magnet.

8. In a secondary electric clock in combination, a disc having a plurality of peripheral projections constituting an armature, an annular pole piece having a plurality of inwardly disposed projections, a shaft for said armature, and an electromagnet having a core surrounding said shaft to magnetize said armature of one polarity, said pole piece being connected with said magnet core whereby it is magnetized of the opposite polarity to cause a partial rotation of said armature, and means to cause additional rotation to position the projections one space forward.

In testimony whereof I hereunto affix my signature.

THADDEUS STEPHENS CASNER.
